UNITED STATES PATENT OFFICE

ALEXANDER S. FALLS, OF GLENCOE, ILLINOIS.

LOCK.

1,361,702.

Specification of Letters Patent.

Patented Dec. 7, 1920.

Application filed April 14, 1919. Serial No. 289,788.

To all whom it may concern:

Be it known that I, ALEXANDER S. FALLS, a citizen of the United States, residing at Glencoe, in the county of Cook and State of Illinois, have invented certain new and useful Improvements in Locks, of which the following is a specification.

My invention relates to a door lock, and more particularly to the type of lock having a pivoted latch.

The primary object of the invention is to provide an improved and inexpensive latch keeper for completely housing the free end of the latch when the latch and keeper are in locking engagement, so as to prevent the latch from being raised or otherwise disengaged from the keeper by the use of unauthorized devices, such, for example, as by inserting a thin element, such as a knife blade, wire, or a piece of cord between the keeper and the edge of the door to which the lock is applied.

Another object of the invention is to provide a novel latch keeper which may be readily applied and used in connection with new locks or with old locks, now in use without requiring changes to be made in the lock casing or latch operating mechanism. In the preferred construction of my invention provision is made for compensating for the worn condition of the latch when the keeper is used in connection with an old lock.

The invention consists in the novel arrangements, constructions and combinations of parts for carrying out the above stated objects, and such other incidental objects as will appear from the following description.

The invention is illustrated in the accompanying drawings, wherein:

Figure 1 is a fragmentary view of a bank teller's cage, showing a locking device, constructed in accordance with my invention, applied thereto;

Fig. 2 is a plan view of the latch keeper shown in Fig. 1, the door and wall of the cage being shown in section;

Fig. 3 is a view similar to Fig. 1, taken from the inside of the cage;

Fig. 4 is a view, partly in section, of the lock and latch keeper shown in the pre-

ceding figures, the view being taken on line 4-4 of Fig. 5;

Fig. 5 is a sectional plan taken on line 5-5 of Fig. 4; and

Fig. 6 is a section of the latch and keeper taken on line 6-6 of Fig. 4.

Like characters of reference designate like parts in the several figures of the drawings.

In the drawings I have shown my invention in connection with a sliding door of the type usually employed for closing the door opening of a bank teller's cage. It will be obvious, however, that the invention is not limited in its application to this particular use or to the type of door illustrated.

In the drawings, 10 designates the side wall of a bank teller's cage which is formed with the usual door opening 11 having a metallic door jamb 12. The door opening is closed preferably, though not necessarily, by a sliding door 13 which, in accordance with the usual construction, operates on the outside of the cage. This door consists of a channel-shaped frame 14 which is covered with a closure strip 15 and supports the metallic mesh construction 16 of the door. The door carries a lock which, for the purpose of convenience, is illustrated in the drawings as being the most conventional type now used by manufacturers of bank teller cages. This lock consists of a casing 17 having a latch 18 pivoted thereon, as indicated at 19. The free end of the latch is formed with the usual hook portion 20 which extends through a slot 21 in the lock casing. The latch is normally held in locking position by means of a spring 22 which is supported on a stud 23, so as to bear on the upper edge of the latch. When it is desired to open the door from the inside of the cage, the latch may be raised by simply rotating a knob 24 which is connected by means of links 25, 26, to the latch. A tumbler mechanism is designated at 27, which mechanism is primarily intended to require the use of a key to raise the latch 18 when it is desired to unlock the door from the outside of the cage. The intended purpose of this general type of lock may be easily evaded, when it is used in connection with

the usual form of latch keeper, by simply inserting a thin element, such as a wire, between the keeper and the edge of the door in a position whereby the latch may be raised or otherwise disengaged from its locking engagement with the keeper. Another customary practice of unlocking these doors is by raising the forward edge until the hook portion of the latch is freed from its engagement with the keeper. These irregularities are overcome and rendered impossible by the present invention by providing a latch keeper structure which completely incloses the free end of the latch when the door is closed, so as to prevent the latch being raised by unauthorized elements, and also avoids the possibility of unlocking the door by raising the forward edge thereof. My improved latch keeper structure consists of a hollow box-like element having an opening 28 in its side through which the hook portion 20 of the latch extends, the upper and lower edges of said openings providing catches 29, 30, for engaging the latch. The element 28 of the keeper is reversibly secured within a housing 31 by means of screws 32, 32. When the keeper is applied in connection with a new lock, the element 28 is positioned in the housing 31 so that the edge 29 will provide the necessary catch for the hook 20 of the latch. When it is applied to an old lock in which the hook portion of the latch is somewhat worn, the element 28 is inverted from the position shown in Fig. 4, so that the edge 30 will provide the catch for the latch. With this construction, it is possible to readily apply the keeper in the place of an old one, and maintain a close fit between the various elements. The housing 31 is provided with ears 33 which may be secured to the door jamb 12 by means of screws 34 or other suitable form of attaching elements. The upper and lower ends of the housing element 31 are cut away as indicated at 35, 36, so as to provide guideways 37 for the forward edge of the door, as indicated in Figs. 2 and 5. This construction prevents the door from being sprung outwardly from the walls of the cage when the door is closed. The vertical edges of the element 28 are rounded, as indicated at 38, to provide guides for directing the end of the latch into the interior of said element. In order to prevent any possibility of the latch being raised by the use of a wire, as above referred to, a hollow sealing element 39 surrounds the outer end of the latch and has a telescopic relation with the element 28 when the door is locked. The inner surfaces 40, 41, of the side and end walls of this element are formed with a taper which serves as a guide for the door when it is being closed, and minimizes the clearance between the walls of the elements 28, 39, so as to prevent any possibility

of disengaging the latch from its locking position by elevating or shaking the door. As a further security against the use of a wire or knife blade for unlocking the door, the element 39 is provided with an extension 42 which surrounds the latch 18 and is seated into the face of the door frame between the flanges of the channel element 14. The element 39 is secured to the door by means of screws 43, 44.

70

75

While I have shown and described my invention in one specific embodiment, it will be obvious that modifications in structure might be made without departure from the spirit of my invention. I therefore do not wish to limit myself to the exact structure shown, except in so far as expressly limited by certain of the appended claims.

80

I claim:

1. The combination of a lock having a pivoted latch element, and a keeper adapted to be engaged by said latch comprising a housing, a catch element supported within said housing, and a seal element adapted to have a telescoping relation with said housing and catch element.

85

2. The combination of a lock having a pivoted latch element, and a keeper adapted to be engaged by said latch comprising a housing, a catch element secured within said housing in spaced relation to the side walls thereof, and a seal element provided with flanges which surround the outer end of said latch and adapted to extend into the space between the walls of the housing and said catch element.

90

95

3. The combination of a lock having a pivoted latch element, and a keeper adapted to be engaged by said latch comprising a housing, a catch element formed with a plurality of catches and secured within said housing in spaced relation to the side walls thereof, and a seal element provided with flanges which surround the outer end of said latch and adapted to extend into the space between the walls of the housing and said catch element.

100

105

4. The combination of a lock having a pivoted latch element, and a keeper adapted to be engaged by said latch comprising a housing, a catch element formed with a plurality of catches and secured within said housing in spaced relation to the side walls thereof, and a seal element having tapered inner surfaces which provide guides having a telescopic relation with the walls of said catch element.

110

115

5. The combination of a lock having a pivoted latch and a latch keeper comprising a housing, a catch element provided with catches of different thickness and detachably secured within said housing so that its position may be readily reversed, and a seal element having a telescopic relation with the walls of said catch and housing member.

120

125

130

6. The combination with a door, of a lock for said door having a pivoted latch, a keeper device adapted to be engaged by said latch when the door is closed, comprising
5 a housing having its ends recessed to provide guides for the edge of the door, and a combined guiding and seating element having flanges which have a telescopic relation with the walls of said housing.
- 10 7. The combination with a door, of a lock for said door having a pivoted latch, a keeper device adapted to be engaged by said latch when the door is closed comprising a housing having its ends recessed to provide
15 guides for the edge of the door, a catch element reversibly supported within the housing in spaced relation to the side of the housing, and a seal element formed with flanges adapted to extend into the space between the walls of said catch and housing
20 elements when the door is closed.
8. The combination with a slide door, of a lock on said door provided with a pivoted latch, a latch keeper supported in a fixed position with relation to said door comprising
25 a housing and a catch member supported therein in spaced relation to the side walls,
- and a sealing element carried by the door and provided with flanges which project into the space between said catch and housing 30 members.
9. The combination with a slide door, of a lock on said door provided with a pivoted latch, a latch keeper supported in a fixed position with relation to said door comprising 35 a housing and a catch member supported therein in spaced relation to the side walls, and a sealing element carried by the door and provided with flanges which project into the space between said catch and housing 40 members, said element surrounding the outer end of said latch and having a flanged portion which is seated into the vertical edge of the door.
10. The combination of a lock having a 45 pivoted latch, and a latch keeper comprising a reversible housing, a catch element provided with catches of different thickness and detachably secured within said housing so that its position may be readily reversed, 50 and a seal element having a telescopic relation with the walls of said catch and housing member.

ALEXANDER S. FALLS.
